METHOD AND APPARATUS FOR
CLEANING COTTONMorris M. Bryan, Jr., Jefferson, Ga., assignor to The
Jefferson Mills, Inc., Jefferson, Ga., a corporation of
GeorgiaFiled Apr. 19, 1965, Ser. No. 449,118
10 Claims. (Cl. 19—200)

This invention relates to a method and apparatus for cleaning cotton fibers, and is more particularly related to a method and apparatus for simultaneously vibrating and drawing out a web of cotton fibers as an intermediate step in a cotton treating process to remove dirt and undesirable short fibers from the mass of cotton and orient the fibers.

Heretofore, expensive cleaning machines have been utilized before the cotton is fed to a carding machine. These previous cleaning machines have consisted of various forms of beaters, jets of air, cylindrical spikes, grid bars, etc. All of these machines have tried to tear up cotton into small bits and clean the small bits; and, they did accomplish some cleaning, but only to a small extent as compared to the present invention since they were attempting to remove trash from cotton fiber aggregates. None of the previous machines have disentangled the cotton fibers to separate the fibers until the fibers are passed through a carding machine.

Thus, no existing methods of processing cotton provide for intentional cleaning of fibers after a web is formed. While the crush roll ("Crosrol Varga") crushes dirt so that it may fall out in subsequent processes such as drawing, roving, spinning, winding and weaving, it does not provide means for removing dirt while the fibers are in web form. Furthermore, while cotton slivers are intentionally drafted to parallelize the fibers therein in equipment known as drafting frames, such drafting functions only to an incidental minor extent, if at all, to clean the fibers since the debris in the sliver has no way to escape due to the thickness of the sliver.

It is impractical to try to remove dirt, undesirable short fibers, and other trash from cotton fiber aggregates or cotton after it is formed into a sliver because the entangled fibers that make up the aggregates and the mass of cotton that makes up a sliver hold the dirt and short fibers too securely and will not permit them to fall out, regardless of the external forces applied.

Because of the fact that cotton fiber aggregates and cotton slivers are difficult to clean, it was determined that it would be desirable to clean the fibers in some stage between the time it is in the aggregate form and the time it is in the sliver form. Between these stages it has been the practice in the industry to treat the cotton in a carding cylinder whereupon the cotton is discharged in the form of a broad thin web with the fibers parallelized to some extent. This web is subsequently processed through a trumpet to form a sliver. While the cotton is in web form the web is very thin so that any debris or undesirable short fibers present therein are necessarily close to the surface and easily removed. However, the fact that the web discharged from the carding cylinder is thin makes it easily torn or damaged by any previously known cleaning process, and treatment of the web for cleaning purposes at this stage has heretofore been unsuccessful in the industry.

Accordingly, this invention discloses cleaning cotton fibers in a wholly new manner in a cotton treating process which comprises vibrating cotton in the form of a web, to shake debris and short cotton fibers away from the web, stretching or drawing out the web as it is vibrated and sucking the debris and short fibers vibrated from the web from the vicinity of the web. The web is vibrated in

2

a direction perpendicular to its plane and stretched longitudinally of its path of travel in the process so that the forces exerted thereon by the vibrations tend to cause the debris and short cotton fibers throughout the length and width of the vibrated span of the web to be propelled away from the web. If the initial vibration does not function to immediately loosen the debris and short fibers, subsequent vibrations and gradual drawing out of the fibers will tend to work the short fibers and debris loose from the web so that they will be subsequently discharged from the web.

The present invention involves the use of fluted rolls arranged in pairs and with the fluted rolls of each pair being closely associated with each other so that the rotation thereof causes the lands or teeth of one fluted roll to mesh with the lands or teeth of another fluted roll. The cotton web is passed between a pair of fluted rolls and the land or tooth of one fluted roll causes the web of cotton to be received in the groove of the opposite fluted roll so that rapid rotation of the pair of fluted rolls causes the web of cotton to vibrate rapidly as it enters and exits the pair of fluted rolls. Also, each succeeding pair of fluted rolls rotates at a faster rate so that the cotton web is drawn out to become progressively thinner between the pairs of fluted rolls. The drawing out and vibrating of the web at this stage improves the quality of the web so that when it is run through the trumpet in the process, a sliver is formed that requires less drawing out to align and clean the fibers to meet the standards of "Superior Carded Yarn," and to qualify as "Combed Yarn" the combing process can even be eliminated.

While it is true that the primary purpose of the fluted roll is to vibrate, shake and stretch or draft the web as it passes through them so that artificial trash, debris and undesirable short fibers are removed, it should be recognized that an additional objective is attained which adds tremendously to the total value of the operation, that a superior parallelization of fibers is attained as the web is acted upon by the fluted rolls.

Heretofore parallelization of fibrous carded stock has been obtained on drawing frames by passing through pairs of rollers several slivers—the product of cards. These slivers are stretched or drafted and parallelization results. However, slivers contain many fibers in a rather bulky state and difficulty is encountered in making the majority of fibers lie parallel with each other and in making the rolls act on the fibers uniformly.

In the machine hereinafter disclosed, the web acted on by the rolls contains separately disentangled fibers very loosely tied together and it can easily be seen that the drafting or stretching action of the fluted rolls acts on each of the individual fibers, the result being that many more of the fibers lie parallel than is the case when bulky masses of fibers such as slivers are drafted or stretched. Tests show that subsequent drawing frame operations for the purpose of parallelization can be substantially reduced or even eliminated in processing cotton treated by this invention.

Accordingly, it is an object of this invention to provide a method and apparatus for rapidly, economically and efficiently drawing out and cleaning cotton.

It is another object of this invention to provide a method and apparatus for vibrating a moving web of cotton at the ends of a span of free travel of the web so as to impart a motion to the web which causes dirt, debris and undesirable short cotton fibers to be discharged from the web.

It is another object of this invention to provide a method and apparatus for drafting or drawing out a web of cotton in a manner which causes the web to be vibrated as it is progressively drawn out so as to align the fibers and to remove any dirt, debris and undesirable short cotton fibers from the web.

Numerous other objects, features, and advantages of the present invention will be apparent from consideration of the following specification, taken in conjunction with the accompanying drawing, in which:

FIG. 1 is a schematic elevational view of the typical type apparatus in which this invention can be utilized;

FIG. 2 is an elevational view, in cross section, of two adjacent pairs of fluted rolls, showing how the rolls act on the cotton web;

FIG. 3 is an end view of the bearings for the pairs of fluted rolls, showing the drive means;

FIG. 4 is an end view of the bearings for the pairs of fluted rolls from the side opposite from FIG. 3, showing the method of synchronizing the fluted rolls of each pair.

Referring now more particularly to the drawings, a system in which the present invention may be used comprises a lickerin 10, a carding cylinder 12, flats 14, a doffer 15, a comb 16, an air suction device 17, a series of fluted drafting rolls 18, a trumpet 19, a pair of calender rolls 20, and a barrel 21. The cotton from the bale (not shown) is fed to the lickerin 10 and passed by the lickerin 10 to the carding cylinder 12 and its flats 14 in a conventional manner. The doffer 15 retrieves the cotton web 25 from the carding cylinder 12 and feeds it to the drafting rolls 18 where it is cleaned and drawn out, and the air suction device 17 removes most of the short cotton fibers and light debris vibrated from the web, while some short fibers and the heavier debris fall to the floor.

As is best shown in FIG. 2, the cotton web 25 is pulled into the plurality of fluted drafting rolls by the first pair of fluted drafting rolls 22 and 23. The fluted drafting rolls are slightly wider than the web 25 and each have a series of lands or teeth 28 and 24, respectively, and grooves 29 evenly spaced around their circumferences. The fluted rolls of each pair are arranged so that when the rolls are rotated, they will be rotated in opposite directions so that the teeth of one roll will pass between the teeth of its opposite roll, within the grooves thereof. The teeth and grooves of one roll, however, do not come into contact with the teeth and grooves of the opposite roll. For instance, the fluted roll 22 rotates in a counterclockwise direction while the fluted roll 23 rotates in a clockwise direction. The teeth 24 of the roll 23 pass between the teeth 28 of the roll 22 such that the grooves 29 of the roll 22 receive the teeth 28. With this arrangement, it can be seen that the cotton web 25 would be forced to take a circuitous path when passing between the rolls 22 and 23, and the circuitous path together with the action of the closely disposed fluted drafting rolls causes the cotton web to be drawn into the rolls by the rotation thereof due to the frictional engagement of the rolls 22 and 23 with the cotton web 25.

After the cotton web 25 passes between the rolls 22 and 23, it is fed to a subsequent pair of rolls, such as rolls 26 and 27, which are substantially identical to the first pair of rolls 22 and 23. The function of the second pair of rolls 26 and 27 is the same as the function of the first pair of rolls 22 and 23 in that the cotton web 25 is drawn into the rolls due to the frictional contact of rolls 26 and 27 with the cotton web 25.

As the drafting rolls 22 and 23 rotate, the teeth of one roll mesh with the teeth of its opposite roll, as exemplified by tooth 28b, in such a manner that, when the tooth 28b reaches a point where it is exactly between the two fluted rolls 22 and 23, it deeply penetrates the groove 29 between the teeth 24a and 24b of the fluted drafting roll 23. As the cotton web is initially drawn between the fluted drafting rolls, it remains in its initial state as it is first engaged between the teeth as shown at 30, however, as the teeth penetrate more deeply into the grooves, the cotton web is progressively stretched as shown at 31, until the teeth are exactly between the fluted rolls, whereupon the cotton web is stretched to its furthest extent as shown at 32. As the teeth begin to withdraw from the grooves 29, the tension imparted to the drawn

cotton web is somewhat relieved and the cotton web leaves the pair of fluted drafting rolls in a somewhat elongated condition.

Referring now to FIG. 3, each of the fluted drafting rolls rotates on an axle 35 which is mounted in bearings 36. The bearings 36 are disposed so that the axles 35 are parallel with one another and means (not shown) are provided for making small adjustments to the axles to maintain the axles of each pair of rolls in an exact parallel disposition and to maintain the rolls of each pair at a prescribed distance from each other.

The lower axle of each pair of rolls has a pulley, such as pulleys 38, 39 and 40, attached thereto. The axle 35 to which pulley 28 is attached also has pulley 41 attached thereto which is engaged by a motor driven belt 42. Pulley 39 is slightly larger than pulley 38, and pulley 40 is slightly larger than pulley 39. Each of the pulleys is driven by a common driving belt 44, of the type generally referred to as a timing belt, so that a pre-determined relationship between the driven pulleys can be maintained. Since the pulley 38 is smaller in diameter than the pulley 39, it can be seen that the belt 44 driven by the pulley 38 will cause the pulley 39 to rotate at a slower rate of speed than the pulley 38. Similarly, the pulley 40 will be driven at a slower rate of speed than the pulley 39. Accordingly, the fluted drafting rolls driven by each of the pulleys will be driven at a rate of speed corresponding to the rate of speed of its driving pulley.

With this arrangement, when the cotton web 25 fed to the fluted rolls driven by the pulley 40 reaches the fluted rolls driven by the pulley 39, it will be received at a faster rate of speed than it was received by the first fluted rolls. Thus, it should be understood that each succeeding pair of fluted drafting rolls is driven at a higher rate of speed than its preceding pair, such that the cotton web is received at a higher rate of speed as it passes through the plurality of fluted drafting rolls 18.

An idler pulley 37 is positioned between the pulleys 38 and 39 so that it bears on the timing belt 44 and insures that the timing belt 44 frictionally engages the pulley 39.

Referring now to FIG. 4, the fluted drafting rolls each have a portion of their ends 45 and 46 beyond the edges of the web coated with chromium steel so that a uniform layer of chrome is present on all the teeth of the rolls. With this arrangement the coated portion of the rolls of a pair of rolls will contact each other when the teeth of the rolls mesh with each other so that the coated teeth will maintain the uncoated teeth in an exact spaced relationship. Thus, the uncoated portion of the fluted drafting rolls of each pair of rolls will be arranged so that the teeth of one roll will always project into the grooves of its opposite roll without contacting the teeth of the opposite roll so that a predetermined space is maintained between the rolls at all times. This arrangement insures that the cotton web 25 which passes between the uncoated portion of the rolls will not be crushed by the teeth of the rolls. Also, any cotton seeds in the web will not be crushed by the teeth of the rolls and the oils in the seeds will therefore not be liberated to wet the web or rolls and have any detrimental effect on the web to inhibit the cleaning process.

Obviously, other methods of maintaining the rolls in spaced relationship can be utilized. For instance, the rolls can be formed with the flutes larger at their ends or external gears can be used.

As is best shown in FIG. 2, as the cotton web 25 leaves the fluted drafting rolls, the teeth of the rolls cause certain vibratory movement in the cotton web. As the tooth 28d is withdrawn from its related groove, the cotton web is allowed to be drawn by the subsequent pair of fluted drafting rolls so that it is supported by the tooth 24c of the fluted drafting roll 23. The tooth that is last to engage the span of the web that is leaving a pair of fluted rolls, and the tooth that is first to engage said span entering

the next pair of fluted rolls impart their velocity characteristics to that end portion of the span engaging each tooth thus creating a vibration of the span. Since the tooth 24c is traveling in a generally downward movement in its clockwise rotation, it can be seen that as long as that tooth supports the cotton web, it will have a downward component of velocity. However, when tooth 24c no longer engages the cotton web, the tooth 28c will impart its velocity characteristics to the cotton web, and since its counterclockwise rotation has a component of velocity which is directed upward, the cotton web will accordingly have an upward component of velocity. Since the cotton web 25 follows generally the velocity characteristics of the teeth of the engaging fluted rolls, it can be seen that a vibratory motion will be imparted to the cotton web on either side of the pairs of the rolls. This vibratory motion is desirable in that any dirt remaining in the cotton web at this point will be vibrated out of the web.

Operation

As the cotton web 25 is sent to the first pair of the series of fluted drafting rolls 18, the intermeshing teeth of the rolls receive the web and force it down into the grooves 29 between the teeth. As the cotton web is forced into the grooves, the frictional engagement of the teeth with the web causes the web to be stretched or drawn out so that the dirt enmeshed in the web will tend to separate from the fibers. As the cotton web leaves the first pair of rolls, a vibratory motion is imparted to the span of web between the first pair of rolls and the second pair of rolls by the teeth of the first pair of rolls disengaging the web 25 and also by the teeth of the second pair of rolls engaging said web. The vibratory motion set up in the web causes the dirt drawn out between the first pair of rolls to be separated from the mass of the web during its span between the pairs of rolls.

As each subsequent pair of rolls operates at a higher rate of speed than the preceding pair of rolls, the slack in the web that might be caused by lengthening the web between the rolls is taken up by the rolls of each succeeding pair. Also, it is desirable to further draw out the cotton web between the pairs of rolls to further loosen the dirt and align the fibers so that the web can be maintained relatively taut between the pairs of rolls to enhance the vibration, drawing out and cleaning of the web. Accordingly, each of the subsequent pairs of rolls operates at a speed slightly faster than necessary merely to receive the length of cotton web discharged by a preceding pair of rolls. In other words, the speed of each subsequent pair of fluted drafting rolls is adequate, not only to receive all the cotton web discharged from a preceding pair of rolls, but also to draw out and lengthen the cotton web in its span between each pair of rolls. Since the web and fluted drafting rolls are oriented in a horizontal plane, it can be seen that the vertical vibratory motion imparted to the web by the rolls will cause a portion of the shorter fibers and lighter debris to be removed upwardly of the web. Ordinarily, some of these lighter elements might fall back on to the web and eventually be carried on into the trumpet 19, however, a suction device 17 is placed vertically above the web 25 in the vicinity of the rolls 18 so that the majority of these lighter elements removed from the web are carried away without settling back onto the surface thereof.

While the invention has been disclosed as comprising a series of pairs of fluted drafting rolls of the same size, and subsequent pairs of rolls rotating at a higher speed than each preceding pair of rolls, it should be understood that in some instances it might be desirable to employ pairs of fluted rolls varying in size, with each subsequent pair of rolls being of larger size than its preceding pair of rolls, and each pair of rolls rotating with the same angular velocity. With this arrangement, the equal angular velocity of each pair of rolls would cause the

succeeding pairs of rolls to pull in more cotton web than the preceding pair of rolls discharged. Thus, with each pair of dissimilarly sized rolls having the same number of teeth thereon, with the larger rolls having larger teeth, it can be seen as is shown in FIG. 2, that the same teeth will simultaneously engage the span of cotton web extending between the pairs of rolls on each revolution of adjacent pairs of rolls. For instance, the tooth 24c will engage the span between the pairs of rolls each time the tooth 26a engages said span. Accordingly, if the adjacent pairs of rolls are properly oriented, the teeth on the first pair of rolls that impart a downward component of velocity to the span of material can be timed to act on the material at the same time the teeth on the subsequent pair of rolls impart a downward component of velocity. For instance, the tooth 24c, which imparts a downward component of velocity to the span of material extending between the pairs of rolls, would act on the span at the same instant that tooth 26a imparts its downward component of velocity on the span of cotton web.

With this arrangement, it can be seen that both ends of the span of cotton web will be vibrated at its ends in the same general direction, viz., upwardly or downwardly, so that the effect on the span of cotton web between the rolls will be to impart a predetermined vibration thereto. This arrangement allows the operator to run the plurality of fluted drafting rolls at such a speed that a harmonic vibration can be set up in the whole length of the span of cotton web. This motion is desirable as opposed to having the ends of the span move in opposite directions since movement in opposed directions at the ends of the span might cause the span to feel the vibratory effect only at its ends near the rolls as illustrated at the left side of FIG. 2, while simultaneous movements in the same direction at the ends of the span cause the span to feel the vibratory effect throughout its length as illustrated at the right side of FIG. 2. Such a vibration has been found to be extremely effective in removing the dirt from the cotton web and in drawing out the cotton web. Also, with such a vibration, smaller vibratory amplitude is required which results in utilizing smaller teeth in the fluted drafting rolls.

Since the portions of the rolls acting on the web do not come into contact with each other, it can be seen that there is no single positive point of contact of the web and the rolls as it might be if the rolls were of a cylindrical configuration and crushed the web therebetween. Thus, there is no single point of release of the web from one pair of rolls to a subsequent pair of rolls so that the effect of the pairs of rolls on the web is to gradually gather the web and gradually release the web as it passes between each pair of rolls. Furthermore, the meshing of the uncoated portion of the teeth of the pairs of rolls is loose enough so that the web is not rigidly held even at the deepest penetration of the teeth of one roll into the grooves of another roll. The net effect of this arrangement is that if a particularly taut portion of cotton web passes between the series of pairs of rolls which does not stretch as readily as the system is designed for, the taut portion of the web is gradually gathered by the teeth, gradually released from the teeth, and even pulled through the teeth by the subsequent faster pair of rolls or the previous slower pair of rolls so that there is never any abrupt stretching of the web which tends to cause a breaking down of the web arrangement of the fibers.

The present invention has been disclosed as specifically showing only adjacent pairs of fluted drafting rolls, however, it should be understood that any number of drafting rolls could be employed at the option of the manufacturer, and the plurality of fluted drafting rolls can be positioned at any number of points in the cleaning process, or in a process other than that exemplified herein. Furthermore, it should be understood that while a particular tooth formation on the fluted drafting rolls has been disclosed in this description, or any number of tooth formations

might be employed without departing from the scope of this invention.

Because of the improved drawing out and cleaning function of the fluted rolls 18, the fibers of the sliver emitted from the trumpet 19 are cleaner and more perfectly aligned than in any other known process and it has been found that when a sliver treated by this invention has been processed through a single drawing process the product is equivalent to the currently known "Superior Carded Yarn." This effectively eliminates the previous necessity of twice drawing out the sliver to attain "Superior Carded Yarn." Furthermore, when a sliver treated by this invention is subjected to two drawing processes, the product is equivalent to the currently known "Combed Yarn." This produces a high quality product while eliminating the slow process of combing the yarn.

Because of its simplicity, this invention costs less to manufacture and maintain, and can be operated at speeds never attained before in the manufacture of yarn.

It will be obvious to those skilled in the art that many other variations can be made in the embodiments chosen for the purpose of illustrating the present invention without departing from the scope thereof as defined by the appended claims.

What is claimed as invention is:

1. An apparatus for cleaning a carded fibrous web comprising means for conducting a carded fibrous web along a path from a carding operation to a condensing operation and web treating means arranged along said path to oscillate said web in a direction substantially normal to said path and also draft said web whereby trash initially entrained within said web becomes dislodged and separated as said web moves along said path.

2. An apparatus according to claim 1 wherein the web treating means includes at least one pair of cooperating rolls arranged to receive said carded fibrous web therebetween, each roll of said pair having a plurality of flutes defining alternating grooves and radially extending projections forming its peripheral surface all of which are generally in alignment with the rotational axis of said roll, said pair of cooperating rolls being arranged in such a manner that the flutes of one roll intermesh with the flutes of the other roll, and means to drive said rolls in opposite rotational directions whereby said carded web is drafted as it passes through said intermeshed flutes and is continuously deflected in an oscillatory manner from said path as it enters and exits from said pair of cooperating rolls.

3. An apparatus according to claim 2 wherein the radially extending projections extend a substantial distance into the opposite corresponding grooves as said flutes

of one roll become intermeshed with said flutes of the other roll.

4. An apparatus according to claim 3 wherein there is a series of successive pairs of said cooperating rolls arranged along said path with each successive pair of rolls in going from the carding operation to the condensing operation having driving means for being driven at a faster rate than the previous pair of rolls.

5. An apparatus according to claim 4 wherein vacuum means are provided adjacent said series of successive pairs of rolls for collecting trash which becomes dislodged and separated from said carded fibrous web as it passes along said path.

6. A method for cleaning a carded fibrous web comprising the steps of conducting a carded fibrous web along a path from a carding operation to a condensing operation, oscillating said web in a direction substantially normal to said path and drafting said web while said web is being conducted along said path to thereby dislodge and separate trash which is initially entrained within said web.

7. A method according to claim 6 wherein said web is periodically oscillated and drafted along said path, said drafting taking place at alternate periods from said oscillation.

8. A method according to claim 6 wherein said web is periodically oscillated and substantially continuously drafted along said path.

9. A method according to claim 6 wherein said oscillation of said web is mechanically induced.

10. A method according to claim 6 including the additional step of applying vacuum to said web during said oscillation and drafting.
